UNITED STATES PATENT OFFICE

131,632

DESIGN FOR A DECK OF CARDS

Antoinette Morré, New York, N. Y.

Application July 25, 1941, Serial No. 102,478

Term of patent 7 years

To all whom it may concern:

Be it known that I, Antoinette Morré, residing in the Borough of Manhattan, city, county, and State of New York, have invented a new, original, and ornamental Design for a Deck of Cards, of which the following is a specification, reference being had to the accompanying drawings, forming part thereof.

In the drawings:

Figures 1, 2 and 3 inclusive are face views of a deck of 36 cards showing my new design. The backs of the cards are conventional.

I claim:

The ornamental design for a deck of cards, as shown and described.

ANTOINETTE MORRÉ.
